Byron D. John
ATTORNEY.

UNITED STATES PATENT OFFICE

THOMAS WILLIAMS, OF TOPEKA, KANSAS

SPUDDING CUSHION FOR DRILLING MACHINERY

Application filed December 9, 1929. Serial No. 412,787.

My invention relates to improvements in spudding cushions for well drilling machinery.

The object of my invention is to provide a cushioning device comprising a pair of semi-elliptical springs in combination with a sheave mounted on the walking beam of a certain type of well drilling equipment to allow the use of wire line instead of rope in the drilling 10 of a well.

A still further object of my invention is to provide a resilient device for attachment to the walking beam of certain types of well drilling equipment in which the resiliency necessary for proper operation is obtained through the use of a plurality of semi-elliptical leaf springs acting against the jerk of the pitman on a wire line.

A still further object of my invention is 20 to provide a cushioning device to be used for spudding with wire lines.

A still further object of my invention is to provide a cushioning device of the kind described in which the resiliency of a leaf type 25 spring absorbs the shock of the tools and permits the use of wire line.

A still further object of my invention is to provide a device of the kind described to give the necessary whip to a wire line when 30 used on certain types of rigs for well drilling.

These and other objects will hereinafter be more fully explained, reference being had to the accompanying drawing, forming part of this specification and wherein like characters 35 apply to like parts in the different views.

Referring to the drawings:

Fig. 1 is an elevation of a well drilling machine illustrating the position of the cushioning device on the walking beam. 40 Fig. 2 is a plan view of the cushioning device positioned on fragmentary portions of the walking beam.

A walking beam comprising two beam members 1 is pivotally mounted at one end 45 to a frame 2 as indicated at A.

A pitman 3 connected at one end to the walking beam at B and at the other to a crank pin 4, rocks the walking beam in accordance with the rotation of the gear 5.

The latter rotates with the gear 6 which is

driven by the pulley 7. The pulley 7 receives its rotation by a belt driven as indicated at C, from a prime mover located in the housing 8.

A mast 9 mounted on the frame at D has a sheave 10 rotatably mounted at its upper extremity. 55

Two semi-elliptical leaf springs 11 are positioned on a cross member 12. This cross member is rigidly connected to the upper side of the walking beam as indicated at E. 60

One end of each of the springs is connected to a second cross member 13 which is rigidly positioned on the lower side of the walking beam as shown at F. A short shaft 14, carried by the other ends of the 65 springs as at G, trunnions a sheave 15 mounted between the springs.

A wire line or cable 16 connected at one end to a spool at S passes over a sheave 17 carried by the frame 2, under the sheave 15 70 on the springs and over the sheave 10 at the top of the mast 9 and thence downward to the well.

The drilling tools are suspended on the other end of the line 16 which is shown entering the hole as at H in Fig. 1. 75

The springs 11 are positioned to react against the face of the sheave 15 on the line 16 as the walking beam is rocked.

The jar of the tools is cushioned by the 80 springs and a whip is imparted to the wire line giving it an effect similar to that of the stretch of manila cable.

The device described permits the use of 85 wire line instead of manila cable and greatly reduces the cost of drilling with regard to cable replacement.

The spudding action of the rig would be 90 very severe on its component parts when wire line is used except for the cushioning action of the leaf springs.

The advantages of my cushioning device for spudding herein described lie in, the reduction of jar on the rig, the economy of operation with regard to the substitution of 95 wire line for manila cable, the resiliency imparted to the wire line at the start as well as at the completion of the work and the whip action of the leaf springs.

Such modifications may be used as lie 100

within the scope of the appended claims and what I claim as new and desire to secure by Letters Patent is:

1. In a cushioning device for use with 5 wire line on well drilling equipment in combination with a walking beam of a rig, a plurality of leaf springs mounted at their center and one end on the walking beam, a sheave trunnioned at the other end of the 10 said springs and bearing against a wire line.
2. In a spudding device to be used in connection with wire lines on drilling rigs, two semi-elliptical leaf springs, a sheave, cross members, the springs positioned on a walking beam by means of the cross members 15 and the sheave rotatably positioned on the springs, and transmitting the motion of the walking beam to a cable.
3. In a device of the kind described to 20 transmit the movement of a walking beam on a drilling rig to a wire line in a spudding operation, two resilient members positioned at their center on a walking beam, one end of each of the resilient members bearing 25 against the walking beam and the other end of each of the resilient members bearing against a wire line, means to prevent wear on the wire line mounted at the last said end of each of the resilient members.
4. In resilient members as connecting 30 means between a spudding pulley and the walking beam of a drilling rig, two laminated springs mounted at their center on the walking beam and affixed at one end to the 35 said beam, the other end of the said springs connected to a pulley, the retraction of the springs being toward the walking beam.
5. In a device of the kind described, a pair 40 of laminated springs in combination with a spudding pulley and a walking beam, the springs fastened at one end and bearing at their center on the walking beam, the pulley 45 rotatably mounted at their other end to provide the necessary whip to a wire line for spudding.
6. In a device to absorb the jar on a rig 50 during spudding operations, in combination with the walking beam of the rig, a leaf spring and a sheave, the leaf spring mounted on the walking beam and the sheave mounted on the leaf spring, the said sheave bearing against a wire line and the said 55 spring acting as cushioning means between the rig and the tools.

55 In testimony whereof I affix my signature.
THOMAS WILLIAMS.
